(57) **CLAIM**

The ornamental design for a display screen with transitional graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. FIG. 1 is a front view of a display screen with transitional graphical user interface in accordance with a first embodiment showing the first image in a sequence of our new design;

FIG. 2 is a second image thereof;

FIG. 3 is a third image thereof;

FIG. 4 is a front view of a display screen with transitional graphical user interface in accordance with a second embodiment showing the first image in a sequence of our new design;

FIG. 5 is a second image thereof; and,

FIG. 6 is a third image thereof.

The outermost broken lines showing of a display screen form no part of the claimed design. The remaining broken lines showing the graphical user interface form no part of the claimed design.

The appearance of the transitional graphical user interface sequentially transitions between the images shown in FIG. 1-FIG. 3 and FIG. 4-FIG. 6. The process or period in which an image transitions to another forms no part of the claimed design.
